(57) **ABSTRACT**

A lighting device may be provided that includes a light emitting module including a substrate and a light emitting device disposed on the substrate; and a case receiving the light emitting module therewithin and including an upper case disposed on the substrate and a lower case in which the substrate is disposed. The lower case includes a seating portion which is coupled to a heat sink. The seating portion is either a projection projecting outward from the outer surface of the lower case or a recess which is formed by digging inward the outer surface of the lower case.

LIGHTING DEVICE

CROSS-REFERENCE TO RELATED APPLICATION

The present application claims priority under 35 U.S.C. §119(e) of Korean Patent Application No. 10-2011-0015986 filed Feb. 23, 2011, No. 10-2011-0015987 filed Feb. 23, 2011 and No. 10-2011-0019266 filed Mar. 4, 2011 the subject matters of which are incorporated herein by reference.

BACKGROUND

1. Field

Embodiments may relate to a lighting device.

2. Background

A light emitting diode (LED) is an energy device for converting electric energy into light energy. Compared with an electric bulb, the LED has higher conversion efficiency, lower power consumption and a longer life span. As these advantages are widely known, more and more attentions are now paid to a lighting apparatus using the LED.

The lighting apparatus using the LED are generally classified into a direct lighting apparatus and an indirect lighting apparatus. The direct lighting apparatus emits light emitted from the LED without changing the path of the light. The indirect lighting apparatus emits light emitted from the LED by changing the path of the light through reflecting means and so on. Compared with the direct lighting apparatus, the indirect lighting apparatus mitigates to some degree the intensified light emitted from the LED and protects the eyes of users.

SUMMARY

One embodiment is a lighting device. The lighting device includes: a light emitting module including a substrate and a light emitting device disposed on the substrate; and a case receiving the light emitting module therewithin and including an upper case disposed on the substrate and a lower case in which the substrate is disposed. The lower case includes a seating portion which is coupled to a heat sink. The seating portion is either a projection projecting outward from the outer surface of the lower case or a recess which is formed by digging inward the outer surface of the lower case.

Another embodiment is a lighting device. The lighting device includes: a lower case including one side; a light emitting module which is disposed on the one side and includes a light emitting device; a lens structure which is disposed on the one side of the lower case in such a manner as to cover the light emitting module and controls light emitted from the light emitting module; a packing structure which is disposed on the one side of the lower case in such a manner as to cover the lens structure; and an upper case which covers the packing structure and is coupled to the lower case.

Further another embodiment is a lighting device. The lighting device includes: a first case which includes a first coupler; a first light emitting module disposed in the first case; a second case which is disposed adjacent to the first case and includes a second coupler; a second light emitting module disposed in the second case; and a connection pad which connects the first case with the second case. The first coupler includes a first coupling hole, wherein the second coupler includes a second coupling hole. The connection pad includes pins which are inserted into the first coupling hole and the second coupling hole.

2

BRIEF DESCRIPTION OF THE DRAWINGS

Arrangements and embodiments may be described in detail with reference to the following drawings in which like reference numerals refer to like elements and wherein:

FIG. 1 is a perspective view of a lighting device according to an embodiment;

FIG. 2 is an exploded perspective view of the lighting device shown in FIG. 1;

10 FIG. 3 is a bottom perspective view of the lighting device shown in FIG. 1;

FIG. 4 is an exploded perspective view of the lighting device shown in FIG. 3;

15 FIG. 5 is a perspective view showing that a plurality of the lighting devices shown in FIG. 1 have been connected to each other;

FIG. 6 is a perspective view of a connection pad shown in FIG. 5;

20 FIG. 7 is an exploded perspective view for describing a modified example of a lower case of the lighting device shown in FIG. 4;

FIG. 8 is a perspective view for describing the flexibility of a cable connected to the lighting device shown in FIG. 1; and

25 FIG. 9 shows a modified example of a part "A" shown in FIG. 3.

DETAILED DESCRIPTION

A thickness or a size of each layer may be magnified, 30 omitted or schematically shown for the purpose of convenience and clearness of description. The size of each component may not necessarily mean its actual size.

It should be understood that when an element is referred to as being 'on' or "under" another element, it may be directly 35 on/under the element, and/or one or more intervening elements may also be present. When an element is referred to as being 'on' or 'under', 'under the element' as well as 'on the element' may be included based on the element.

An embodiment may be described in detail with reference 40 to the accompanying drawings.

FIG. 1 is a perspective view of a lighting device according to an embodiment. FIG. 2 is an exploded perspective view of the lighting device shown in FIG. 1. FIG. 3 is a bottom perspective view of the lighting device shown in FIG. 1. FIG. 4 is an exploded perspective view of the lighting device shown in FIG. 3.

Referring to FIGS. 1 to 4, the lighting device according to the embodiment may include an upper case 100, a packing structure 200, a lens structure 300, a light emitting module 400 and a lower case 500.

50 The upper case 100 is coupled to the lower case 500 and forms a body of the lighting device according to the embodiment. The upper case 100 and the lower case 500 may be strongly coupled with each other by means of a coupling 55 means like a coupling screw "B", etc. Since the upper case 100 and the lower case 500 may be separated from each other, it is possible to easily maintain and repair the broken or damaged parts internally disposed.

60 A coupled body formed by the coupling of the upper case 100 and the lower case 500 may have a hexahedral shape. Here, the shape of the coupled body is not limited to be hexahedral. For example, the coupled body may have a cylindrical shape or polyhedral shape.

65 A predetermined receiving space may be located between the upper case 100 and the lower case 500. The packing structure 200, the lens structure 300 and the light emitting module 400 are disposed in the receiving space. Specifically,

the light emitting module **400** is disposed on the lower case **500**. The lens structure **300** covering the light emitting module **400** is disposed on the lower case **500**. The packing structure **200** covering the lens structure **300** is disposed on the lower case **500**.

The lower case **500** may be formed of a material having a heat radiating characteristic. For example, the material of the lower case **500** may include a metallic material, and specifically at least one of Al, Ni, Cu, Au or Sn. Additionally, the surface of the lower case **500** may be plated with the metallic material.

Like the lower case **500**, the upper case **100** may be formed of a material having a heat radiating characteristic. However, the material of the upper case **100** is not limited to this. Specifically, the material of the upper case **100** may be a common plastic material or a synthetic resin material, each of which has no heat radiating characteristic.

The upper case **100** or the lower case **500** transfers heat generated from the light emitting module **400** to a heat sink **600** or radiates the heat itself. Here, the upper case **100** and the lower case **500** may include a plurality of fins (not shown) in order to more efficiently radiate the heat. The fins (not shown) increase the surface areas of the upper case **100** and the lower case **500**, so that the heat generated from the light emitting module **400** can be effectively transferred or radiated.

The upper case **100** includes a shape of a quadrangular box and an opening "H" allowing light passing through the lens structure **300** to be emitted outward. The upper case **100** also includes holes into which the coupling screws "B" are inserted.

The lower case **500** may have a quadrangular flat plate shape. However, the shape of the lower case **500** is not limited to this. For example, the lower case **500** may have a polygonal flat plate shape.

The lower case **500** includes a coupler **510**. The coupler **510** may be a protrusion projecting outward from each corner of the lower case **500**.

Through the coupling of the lower case **500** and the upper case **100**, the couplers **510** of the lower case **500** are placed at the corners of the upper case **100** respectively. Therefore, the coupled body formed by the coupling of the lower case **500** and the upper case **100** may have actually a hexahedral shape.

In FIGS. 1 to 4, it is shown that the coupler **510** has been formed at each corner of the lower case **500**. However, there is no limit to where the coupler **510** is formed. The coupler **510** may be disposed only at some corners selected among all the corners of the lower case **500**, or may be disposed on the circumference of the lower case **500** instead of the corner of the lower case **500**.

The coupler **510** includes a first coupling hole **511** into which the coupling screw "B" which has passed through the upper case **100** is inserted. The upper case **100** and the lower case **500** can be securely coupled to each other by passing the coupling screw "B" through the upper case **100** and inserting the coupling screw "B" into the first coupling hole **511**. The first coupling hole **511** may have a shape projecting from the coupler **510** toward the center of the lower case **500**.

The coupler **510** includes a second coupling hole **513**. The second coupling hole **513** is used for connecting a plurality of the lighting devices shown in FIG. 1. This will be described in detail with reference to FIG. 5.

FIG. 5 is a perspective view showing that a plurality of the lighting devices shown in FIG. 1 have been connected to each other.

A second lighting device **U2** and a third lighting device **U3** are disposed adjacent to each other on the basis of a first lighting device **U1**.

The coupler **510** of the first lighting device **U1** come in contact with the couplers of other two neighboring lighting devices. The second coupling hole **513** of the first lighting device **U1**, the second coupling hole of the second lighting device **U2** and the second coupling holes of the other two lighting devices are disposed adjacent to each other.

A connection pad "P" is inserted into the four adjacent coupling holes **513**. The four adjacent lighting devices may be coupled to each other by the connection pad "P". Therefore, 10 the coupled four lighting devices can be used as one lighting device. The connection pad "P" will be described with reference to FIG. 6.

FIG. 6 is a perspective view of the connection pad "P" shown in FIG. 5.

Referring to FIG. 6, the connection pad "P" includes a plate **520** and four pins **525**. The four pins **525** project outward from the bottom surface of the plate **520** and are inserted into the four coupling holes **513** shown in FIG. 4.

The top surface of the plate **520** may be disposed on the 20 same plane with the outer surface of the upper case of the first lighting device **U1** shown in FIG. 5.

As shown in FIGS. 1 to 6, the lighting device according to the embodiment has an advantage that it can be connected to other lighting devices which are the same as the lighting 25 device itself. Therefore, when one lighting device shown in FIG. 1 is not able to provide desired brightness, a user has an advantage of obtaining desired brightness by connecting a plurality of the lighting devices shown in FIG. 1.

Referring back to FIGS. 1 to 4, the bottom surface of the 30 lower case **500** includes a seating portion **530** in which the heat sink **600** is disposed.

The seating portion **530** may be a recess which is formed by digging a portion of the bottom surface of the lower case **500** to a predetermined depth. A portion of the heat sink **600** is disposed in the recess **530**. Specifically, a portion of the heat sink **600** is inserted into the recess **530**. Here, the seating portion **530** is not limited to the recess. This will be described with reference to FIG. 7.

FIG. 7 is an exploded perspective view for describing a 40 modified example of the lower case of the lighting device shown in FIG. 4.

Referring to FIG. 7, a seating portion **530'** may be a projection projecting outward from the bottom surface of the lower case **500**. When the seating portion **530'** is a projection, 45 the heat sink **600** may have a recess (not shown) into which the projection **530'** is inserted.

Referring back to FIGS. 1 to 4, the seating portion **530** may be disposed in the bottom surface of the lower case **500**, particularly, under the light emitting module **400**. Specifically, the seating portion **530** is disposed at the central portion of the bottom surface of the lower case **500**. The light emitting module **400** is disposed at the central portion of the top surface of the lower case **500**. Since the light emitting module **400** generates the largest amount of heat, the seating portion **530** is disposed just under the light emitting module **400** in the bottom surface of the lower case **500**.

The heat sink **600** is coupled to the seating portion **530** of the lower case **500**. Here, the heat sink **600** may be coupled to the seating portion **530** of the lower case **500** without a separate coupling means. Specifically, the heat sink **600** may be coupled to the lower case **500** by inserting a portion of the upper portion of the heat sink **600** into the recess **530** of the lower case **500**. Additionally, the heat sink **600** may be easily separated from the lower case **500**. In the lighting device 60 according to the embodiment, the recess **530** of the lower case **500** allows the heat sink **600** to be easily attached or removed without a separate coupling means.

The lighting device according to the embodiment does not necessarily require the heat sink **600** which occupies the most weight and thickness of a conventional lighting device. Therefore, the lighting device according to the embodiment can be smaller and lighter. Also, it is possible to reduce the cost of the heat sink **600** in the total manufacturing cost of the lighting device.

Further, the lighting device according to the embodiment is able to semi-permanently use the one heat sink **600**.

The heat sink **600** may have a plurality of heat radiating fins **610**. The plurality of the heat radiating fins **610** increase the surface area of the heat sink **600** and improve a heat radiation efficiency.

The light emitting module **400** is disposed in the lower case **500** and may include a substrate **410** and a plurality of light emitting devices **430** disposed on the substrate **410**.

The substrate **410** may have, as shown in the drawings, a disc shape. However, the shape of the substrate **410** is not limited to this. The substrate **410** may be formed by printing a circuit on an insulator and may include an aluminum substrate, a ceramic substrate, a metal core PCB or a common PCB.

The substrate **410** is disposed on the top surface of the lower case **500**.

The plurality of the light emitting devices **430** are arranged on one side of the substrate **410**. The one side of the substrate **410** may have a color capable of efficiently reflecting light, for example, white color. The other side of the substrate **410** comes in contact with the top surface of the lower case **500**.

The substrate **410** is electrically connected to a cable "C" shown in FIG. 8. The substrate **410** is supplied with an electric power through the cable "C".

The substrate **410** may include a DC converter or a protective device. The DC converter converts AC to DC and supplies the DC. The protective device protects the lighting device from ESD, a Surge phenomenon or the like.

A heat radiating plate (not shown) may be disposed on the bottom surface of the substrate **410**. The heat radiating plate (not shown) may efficiently transfer the heat generated from the light emitting module **400** to the lower case **500**. The heat radiating plate (not shown) may be formed of a material having thermal conductivity. For example, the heat radiating plate may be a thermal conduction silicon pad or a thermal conductive tape.

The plurality of the light emitting devices **430** are disposed on the substrate **410**. Here, the plurality of the light emitting devices **430** may be disposed on the substrate **410** in the form of an array. The shapes and the number of the plurality of the light emitting devices **430** may be variously changed according to needs.

The light emitting device **430** may be a light emitting diode (LED). At least one of a red LED, a blue LED, a green LED or a white LED may be selectively used as the light emitting device **430**.

The lens structure **300** may include a lens unit **310** and an outer frame **330**. The lens structure **330** receives the light emitting module **400**. Specifically, the cylindrical outer frame **330** surrounds the side of the substrate **410**, and the lens unit **310** is disposed on one side of the substrate **410**. As a result, the light emitting module **400** is received in the lens structure **300**.

The lens unit **310** includes at least one dorm-shaped lens **315**. Here, the dorm-shaped lens **315** may be changed in various forms if necessary, for example, a hemispherical shape, a concave shape, a convex shape or the like.

When the lens **315** of the lens unit **310** has a hemispherical shape, although not specially shown in the drawings, the

bottom surface of the lens **315**, that is to say, a light incident surface may have an irregular shape or a prism shape in order to improve efficiency and obtain a desired light distribution.

The lens **315** controls light emitted from the light emitting module **400**. Here, the control of the light means diffusion or collection of the light from the light emitting module **400**. Specifically, when the light emitting device **430** of the light emitting module **400** is a light emitting diode, the lens **315** is able to diffuse the light from the light emitting device **430**. Additionally, the lens **315** is also able to collect the light from the light emitting device **430** instead of diffusing.

The lens **315** may one-to-one correspond to the light emitting device **430** of the light emitting module **400**. That is, the number of the lenses **315** corresponds to the number of the light emitting devices **430**. For example, as shown in FIG. 2, when 8 light emitting devices **430** are disposed on the substrate **410**, 8 lenses **315** one-to-one correspond to the 8 light emitting devices **430**. Here, the lens **315** may one-to-many correspond to the light emitting device **430** of the light emitting module **400**. In other words, one lens **315** may correspond to two or more light emitting devices **430**.

The lens **315** may include a fluorescent material (not shown). The fluorescent material may be a yellow fluorescent material, a green fluorescent material or a red fluorescent material. When the light emitting device **430** of the light emitting module **400** is a blue light emitting diode, the lens **315** may include at least one of the yellow, green and red fluorescent materials. Due to the fluorescent material included in the lens **315**, a color rendering index (CRI) of light emitted from the lighting device according to the embodiment can be improved.

The outer frame **330** is disposed on the top surface of the lower case **500** in such a manner as to cover the light emitting module **400**.

The outer frame **330** is disposed on the top surface of the lower case **500**, so that the lens unit **310** is spaced apart from the light emitting device **430** of the light emitting module **400** at a certain interval. Therefore, the outer frame **330** forms a predetermined space between the lens unit **310** and the light emitting device **430**. When the light emitting device **430** of the light emitting module **400** is a light emitting diode, a beam angle of light emitted from the light emitting device **430** is approximately 120°. In order to obtain a designer's desired light distribution by using the beam angle, a certain interval "G1" is required between the light emitting device **430** and the lens unit **310**.

The outer frame **330** is received in the packing structure **200**. Specifically, the outer frame **330** is surrounded by the packing structure **200**. Therefore, the packing structure **200** protects the outer frame **330** from external impact.

The lens structure **300** may be injection-molded by using a light-transmitting material. The material of the lens structure **300** may be implemented by glass or a plastic material such as poly methyl methacrylate (PMMA) or polycarbonate (PC) or the like.

The packing structure **200** is disposed on the lower case **500** and receives the lens structure **300**. Specifically, the packing structure **200** is disposed on the top surface of the lower case **500** in such a manner as to cover the lens structure **300**.

The packing structure **200** is disposed between the upper case **100** and the lower case **500**, which prevents water and impurity from penetrating into the lens structure **300** and the light emitting module **400**. The packing structure **200** is able to protect the lens structure **300** and the light emitting module **400** from external impact.

The packing structure **200** may have a circular ring shape to surround the outer frame **330** of the lens structure **300**.

The packing structure 200 may be formed of a material which easily absorbs shock without allowing water to penetrate thereinto. For example, the packing structure 200 may be formed of a waterproof rubber, a waterproof silicon material or the like. Here, when the packing structure 200 is formed of an elastic material such as the rubber or the silicon material, the packing structure 200 is pressed between the upper case 100 and the lower case 500.

The lighting device according to the embodiment shown in FIGS. 1 to 4 is able to improve the flexibility of a cable supplying electric power to the lighting device. Hereafter, this will be described with reference to FIG. 8.

FIG. 8 is a perspective view for describing the flexibility of the cable connected to the lighting device shown in FIG. 1.

Referring to FIGS. 3 and 8, a part "A" is equipped with an electric wire "C" supplying electric power to the lighting device according to the embodiment. The electric wire "C" is electrically connected to the light emitting module 400 shown in FIG. 2 and supplies electric power to the light emitting module 400. Here, the electric wire "C" may be a general cable "C". Hereafter, the electric wire "C" will be described by assuming that the electric wire "C" is a cable "C".

The cable "C" can freely move to the upper case 100 or the lower case 500. A structure for improving the flexibility of the cable "C" will be described in detail with reference to FIG. 4.

Referring to FIG. 4, the upper case 100 includes an insertion recess 110 and an upper seating recess 130. The packing structure 200 includes a projection 210 and a cover recess 230. The lower case 500 includes a lower seating recess 550.

In the coupling of the packing structure 200 and the upper case 100, the insertion recess 110 of the upper case 100 receives the projection 210 of the packing structure 200.

The cable "C" is seated in the upper seating recess 130 of the upper case 100. When the cable "C" is expected to be disposed toward the upper case 100, the upper seating recess 130 receives the cable "C".

The projection 210 of the packing structure 200 has a shape projecting outward from one side of the packing structure 200. The projection 210 is received in the insertion recess 110 of the upper case 100. Here, a portion of the projection 210 is exposed outward.

The projection 210 includes the cover recess 230. A portion of the cable "C" is disposed in the cover recess 230. The cover recess 230 protects the cable "C" and prevents the movement of the cable "C" in the lighting device.

The cable "C" disposed in the cover recess 230 is pressed between the packing structure 200 and the top surface of the lower case 500. Therefore, water or impurity which is introduced along the surface of the cable "C" is blocked.

The cable "C" is seated in the lower seating recess 550 of the lower case 500. When the cable "C" is expected to be disposed toward the lower case 500, the lower seating recess 550 receives the cable "C".

The insertion recess 110 and the upper seating recess 130 of the upper case 100, the projection 210 and the cover recess 230 of the packing structure 200, and the lower seating recess 550 of the lower case 500 allow the cable "C" electrically connected to the light emitting module 400 to freely move to the upper case 100 or the lower case 500 and to be disposed in the upper case 100 or the lower case 500. Therefore, the lighting device according to the embodiment has an advantage of improving the flexibility of the cable "C". Also, as shown in FIG. 5, the plurality of the lighting devices according to the embodiment can be connected with each other regardless of the disposition of the cable "C".

FIG. 9 shows a modified example of a part "A" shown in FIG. 3.

A modified example shown in FIG. 9 shows that the upper case 100 does not include the upper seating recess 130 shown in FIG. 4. In this case, the cable "C" is disposed in the lower seating recess 550 of the lower case 500.

Unlike the modified example shown in FIG. 9, the lower case 500 may not include the lower seating recess 550, and the upper case 100 may include the upper seating recess 130 shown in FIG. 4. In this case, the cable "C" is disposed in the upper seating recess 130 of the upper case 100.

Any reference in this specification to "one embodiment," "an embodiment," "example embodiment," etc., means that a particular feature, structure, or characteristic described in connection with the embodiment is included in at least one embodiment of the invention. The appearances of such phrases in various places in the specification are not necessarily all referring to the same embodiment. Further, when a particular feature, structure, or characteristic is described in connection with any embodiment, it is submitted that it is within the purview of one skilled in the art to affect such feature, structure, or characteristic in connection with other ones of the embodiments.

Although embodiments have been described with reference to a number of illustrative embodiments thereof, it should be understood that numerous other modifications and embodiments can be devised by those skilled in the art that will fall within the spirit and scope of the principles of this disclosure. More particularly, various variations and modifications are possible in the component parts and/or arrangements of the subject combination arrangement within the scope of the disclosure, the drawings and the appended claims. In addition to variations and modifications in the component parts and/or arrangements, alternative uses will also be apparent to those skilled in the art.

What is claimed is:

1. A lighting device comprising:
a light emitting module which includes a substrate and a light emitting device disposed on the substrate; and
a case which receives the light emitting module therewithin and includes an upper case disposed on the substrate and a lower case in which the substrate is disposed,
wherein the lower case includes a seating portion which is coupled to a heat sink, and wherein the seating portion is either a projection projecting outward from the outer surface of the lower case or a recess which is formed by digging inward the outer surface of the lower case.

2. The lighting device of claim 1, wherein the seating portion is disposed under the light emitting module.

3. The lighting device of claim 1, further comprising a lens structure which is disposed on the lower case and receives the light emitting module; and a packing structure which is disposed on the lower case and receives the lens structure, wherein the lens structure comprises an outer frame which surrounds the substrate of the light emitting module and comprises a lens unit which is disposed on the substrate and includes lenses corresponding to the light emitting devices.

4. The lighting device of claim 3, wherein the outer frame of the lens unit causes the lens and the light emitting device to be spaced from each other at a predetermined interval.

5. The lighting device of claim 3, wherein the lens comprises at least one of yellow, green and/or red fluorescent materials.

6. The lighting device of claim 3, wherein further comprising a cable which is electrically connected to the substrate of the light emitting module, wherein the packing structure comprises a cover recess in which the cable is disposed and a projection which includes the cover recess and projects out-

ward, wherein the upper case comprises an insertion recess into which the projection of the packing structure is inserted, and wherein the lower case comprises a lower seating recess into which the cable is inserted.

7. The lighting device of claim 6, wherein the upper case comprises an upper seating recess into which the cable is inserted.

8. The lighting device of claim 6, wherein the lower case as well as the packing structure presses the cable.

9. A lighting device comprising:

a lower case which includes one side;

a light emitting module which is disposed on the one side and includes a light emitting device;

a lens structure which is disposed on the one side of the lower case in such a manner as to cover the light emitting module and controls light emitted from the light emitted module;

a packing structure which is disposed on the one side of the lower case in such a manner as to cover the lens structure; and

an upper case which covers the packing structure and is coupled to the lower case.

10. The lighting device of claim 9, wherein the lower case comprises another side corresponding to the one side, wherein the another side of the lower case comprises a seating portion which is coupled to a heat sink, and wherein the seating portion is either a projection projecting outward from the outer surface of the lower case or a recess which is formed by digging inward the outer surface of the lower case.

11. A lighting device comprising:

a first case which includes a first coupler;

a first light emitting module disposed in the first case;

a second case which is disposed adjacent to the first case and includes a second coupler;

a second light emitting module disposed in the second case; and

a connection pad which connects the first case with the second case,

wherein the first coupler includes a first coupling hole, wherein the second coupler includes a second coupling hole, and wherein the connection pad includes

pins which are inserted into both the first coupling hole and the second coupling hole.

12. The lighting device of claim 11, wherein the first case comprises a first lower case including the first coupler and comprises a first upper case which is coupled to the first lower case, wherein the first lower case is a plate including at least one corner, and wherein the first coupler is disposed at the corner of the plate.

13. The lighting device of claim 12, further comprising:

a first lens structure which receives the first light emitting module, is disposed on the first lower case and controls light emitted from the light emitting module; and

a first packing structure which receives the first lens structure and is disposed between and pressed by the first lower case and the first upper case.

14. The lighting device of claim 11, wherein each of the first and the second cases comprises a seating portion which is coupled to a heat sink, and wherein the seating portion is either a projection projecting outward from the outer surfaces of the first and the second cases or a recess which is formed by digging inward the outer surfaces of the first and the second cases.
